[57] CLAIM

The ornamental design for an office table, as shown and described.

DESCRIPTION

FIG. 1 is a front perspective view of an office table showing our new design;

FIG. 2 is a top perspective view of the office table shown in FIG. 1;

FIG. 3 is a front elevational view of the office table shown in FIGS. 1 and 2, the rear elevational view thereof being a mirror image of FIG. 3;

FIG. 4 is a top plan view of the office table shown in FIGS. 1 and 2;

FIG. 5 is a left side elevational view of the office table shown in FIGS. 1 and 2;

FIG. 6 is a right side elevational view of the office table shown in FIGS. 1 and 2; and

FIG. 7 is a bottom plan view of the office table shown in FIGS. 1 and 2.

FIG. 1

FIG. 2

FIG. 3

FIG. 4

FIG. 5

FIG. 6

FIG. 7
